UNITED STATES PATENT OFFICE

146,481

DESIGN FOR A COMBINED TYPEWRITER
ERASER, BRUSH, AND CHALK HOLDER

Olive C. Manheimer, Cleveland, Ohio

Application May 13, 1946, Serial No. 129,641

Term of patent 7 years

(CL. D74—7)

To all whom it may concern:

Be it known that I, Olive C. Manheimer, a citizen of the United States, residing at Cleveland, county of Cuyahoga, and State of Ohio, having invented a new, original, and ornamental Design for Combined Typewriter Eraser, Brush, and Chalk Holder, of which the following is a specification, reference being had to the accompanying drawing, forming part thereof.

Fig. 1 is a front elevational view of a combined typewriter eraser, brush, and chalk holder, showing my new design;

Fig. 2 is a side elevational view of the article;

Fig. 3 is a rear elevational view of the side opposite that shown in Fig. 1;

Fig. 4 is a top plan view of the article; and

Fig. 5 is a bottom plan view of the article.

I claim:

The ornamental design for a combined typewriter eraser, brush, and chalk holder, substantially as shown.

OLIVE C. MANHEIMER.
